UNITED STATES PATENT OFFICE

102,995

DESIGN FOR A PAPER KNIFE

Robert H. Stewart, Detroit, Mich.

Application December 8, 1936, Serial No. 66,379

Term of patent 3½ years

To all whom it may concern:

Be it known that I, Robert H. Stewart, a citizen of the United States, residing at Detroit, county of Wayne, in the State of Michigan, have invented a new, original, and ornamental Design for a Paper Knife, of which the following is a specification, reference being made to the accompanying drawing, forming part thereof.

Fig. 1 is a front view of a paper knife showing my new design.

Fig. 2 is a side view of my paper knife.

Fig. 3 is an enlarged sectional view taken on lines 3—3 of Fig. 1.

I claim:

The ornamental design for a paper knife as shown.

ROBERT H. STEWART.
